TUNING MEANS FOR RADIO RECEIVERS
AND THE LIKE

Roy Coles Wilks, South Yarra, Victoria, Australia

Application September 21, 1945, Serial No. 617,804
In Australia March 29, 1945

2 Claims. (Cl. 116—124.1)

1

This invention relates to tuning means for radio receivers and the like and has particular reference to the means for operating the dial indicator or pointer in synchronism with the tuning means.

More especially the invention relates to a device according to my U. S. Patent No. 2,364,764, which includes an indicator pointer connected to a nut member which encircles a screw-threaded rod having a driving connection with the adjustable element of the tuning means, provision being made to prevent the nut member from turning with the screw-threaded rod so that when the latter is rotated to adjust the tuning means, the nut member will be moved along the screwed rod and impart corresponding movement to the indicator pointer.

My aforesaid specification also discloses an automatic stop device adapted to resist over-turning of the operating rod after the tuning means has reached its extreme adjusted positions.

My patented devices have been found to be very efficient and generally satisfactory in operation, but I find that it is still possible to improve their operating characteristics by providing means whereby the turning knob of the screwed rod is released from the latter upon the tuning means reaching either of its extreme adjusted positions.

While the automatic stop device previously referred to is generally effective in operation, it might yet be that a determined attempt to turn the operating knob after the tuning means has reached one of its extreme positions, would lead to the pins of the stop device being broken, whereupon serious damage and misalignment would arise.

This deficiency is overcome by the present improvements in a simple and efficient manner as will be readily appreciated hereinafter.

According to the present improvements, I provide a connection between the turning knob and the screwed operating rod which is normally a fast driving connection but which, upon the automatic stop device coming into play, will be automatically caused to slip, so that continued turning of the operating knob will not be communicated to the screwed rod.

A construction which is at present preferred will now be described with reference to the accompanying drawings, in which—

Figure 1 is a side elevation of radio tuning means incorporating the present improvements.

Figure 2 is an enlarged elevation of a nut member and associated parts.

Figure 3 is a cross section of Figure 2.

Figure 4 is a sectional view on line IV—IV of Figure 3.

Figure 5 is a sectional elevation of a driving

2

connection between the operating rod and the turning means.

Figure 6 is a sectional elevation of a connection between the turning knob and the operating rod.

Figure 7 is an end view of Figure 6.

In accordance with the illustrated form of the invention, the operating rod 6 is screw threaded for a suitable part of its length, such screw threaded portion 6a being advantageously in the form known as an "Archimedian twist drill" which, in itself, is an advantage on account of its cheapness compared with an equivalent screwed shaft which is milled to high precision standards. As will appear hereinafter extreme accuracy and uniformity in the formation of this screw threaded portion is not essential for the reason that such irregularity as may exist will be fully compensated for by the improved nut member.

This nut member 7 is formed of two halves or sections 7a and 7b which extend lengthwise of the rod 6, and the semi-circular interior of each section is internally screw threaded in a manner complementary to the screw threaded portion 6a of the rod.

Both sections of the nut member are provided adjacent their opposite ends with two circumferentially extending grooves 8 within each of which is accommodated a coiled spring 9. The ends 10 of each spring 9 are connected to a tension adjustment plate 11 which extends lengthwise adjacent one of the nut sections, preferably the rear nut section 7b. This nut section is provided with an outstanding guide pin 12 which passes freely into a guide hole formed in the tension adjustment plate 11. This plate is also provided with screw threaded holes, one on each side of the guide pin, to receive adjusting screws 13, the inner end of which bear against the exterior of the rear nut section 7b which may have small depressions to receive the inner ends of the screws.

By tightening or slackening one or other of the screws 13, the tension of the springs 9 will be controlled so as to cause the nut sections to be resiliently clamped with any desired degree of pressure around the screw threaded portion of the shaft. In this manner, tolerance or back lash between the nut member and the screw thread or irregularity in the formation of the latter can be overcome by initial adjustment and/or by the automatic resiliency provided by the springs and associated parts.

The indicator pointer 14 may be attached at its inner end by screws or the like to one of the nut sections and preferably the rearmost section 7b.

To this same nut section 7b there may also be attached a depending guide 16 which is adapted at its lower or rear end to slidably engage a

slotted rod 17 that extends parallel with the screw threaded rod 6. This slotted rod and the operating rod may be supported at the ends by columns 18 attached to the chassis 19 of the receiver.

The depending guide member may take various forms. According to one example it may consist of a strip 21 of flat sided or rectangular shape which projects into the slotted rod and is capable of being turned about a perpendicular axis, as by being connected at its upper end by a screw and nut 22 to its nut section 16, whereby it may be ensured that opposite edges of the slot in the rod will be engaged by opposite edges of the guide strip. Such an arrangement ensures that the nut member will be prevented from any side play or wobbling and will be effectively guided in its lengthwise movement consequent upon rotation of the screw threaded shaft.

Referring now to the drive between the screw threaded rod and the adjustable element of the tuning means e. g. a gang of condensers 23, this driving connection combines the functions of a toothed gear drive and a friction drive. In explanation thereof it may be pointed out if a toothed gear drive alone is used then it is practically unavoidable that back lash will occur between the toothed gears. If, on the other hand, the drive is effected solely by friction, then "creeping" would be likely to arise. Either of these faults would prevent synchronisation between the driving means and the dial indicator from being maintained indefinitely.

According to a preferred construction of the combination drive as more clearly illustrated in Figures 1 and 5 of the drawings, the tuning condenser spindle 24 has affixed thereto a disc 26 which for a portion of its periphery is provided with gear teeth 27. This toothed portion meshes with a toothed pinion 28 which may be formed on a fly wheel that is secured to sleeve or bush 29 which in turn is made fast to the operating rod 6. This pinion 28 is surrounded by an annular flange 31, that is integral with the sleeve 29. A nut 32 which screws on to one end of the sleeve 29 provides a bearing face for one end of a spring 33 which presses a collar 34 into engagement with flange 31. To ensure that the position of the nut 32 will be secured at a predetermined position on the sleeve 29 a screw 36 is adapted to bear upon the screwed portion of the sleeve 29. A flywheel 37 is attached to an extension of the sleeve 29 to make the travel of the indicator pointer 16 substantially even and devoid of any jerky movements.

The pinion is thus almost completely concealed by and between the flange 31 and the collar 34 which are yieldingly pressed into engagement by the spring 33. However, the toothed portion of the disc 26 on the condenser spindle 24 projects between the inner faces of the flange and the collar in order to mesh with the pinion 28.

Thus it will be seen that the drive is effected partly by intermeshing of the two toothed members 26, 28 and partly by the frictional grip created by the compression spring 33 causing the collar 34 and the annular flange 31 to closely engage opposite faces of the peripheral portion of the toothed disc 26.

The automatic stop device for resisting continued turning of the operating rod after the tuning means has reached either of its extreme adjusted positions is advantageously as disclosed in my aforesaid Patent No. 2,364,764.

Referring now to the connection between the turning knob and the screwed operating rod, a

preferred construction and arrangement is shown in Figures 1, 6 and 7. According thereto, the operating rod 6 is provided near one end with a plate or disc member 38 which may have a hub 39 by which it is secured, as by set screws to the rod. Disposed face to face with this fixed plate or disc, is another plate or disc 41 which is considerably wider or thicker than the first disc, and encircles the operating rod 6 without being attached thereto. The bore of the second disc is substantially greater than the diameter of the operating rod, but such disc is maintained concentric therewith by fitting around a reduced cylindrical neck portion 42 of a collet or collar 43 which is also free to rotate upon the operating rod.

A spring member 44 extends between the shoulder formed by the stepping of the collar and the outer face of the second disc. While this spring member may take various forms, I have found it advantageous to employ a spring in the form of a spider, having a series of circumferentially spaced radially projecting tongues, 44a (Figure 7), the outer ends of which bear in dimples 46 formed in the outer face of the second disc 41. The pressure of the spring 44 is sufficient to normally maintain the second disc 41 in driving engagement with the first or fixed disc 38, but permits of slip between the two discs as soon as the screwed rod 6 is prevented from further rotation by the automatic stop device.

The operating knob 47, which may be of any suitable form, is attached to the outer end portion of the collar 43 by set screws or the like, while a washer 48 and a pin 49 may be fitted at the outer end of the collar in order to prevent the latter from sliding rearwardly off the rod.

It is desirable to provide for adjustment of the spring pressure so that the action of the driving connection will not be too fierce nor too easy. For this purpose, a pin and slot device or the equivalent may be associated with the main part of the collar adjacent the spring member, in order to permit of lengthwise adjustment whereby the pressure of the spring against the second disc may be increased or decreased. In this connection, it is of importance that the second disc should be of sufficient width or thickness to permit the reduced neck of the collar to remain within the bore of the second disc at all positions of adjustment.

The aforesaid construction and arrangement of the connection between the turning knob and the screwed operation rod has the further advantage that it is inexpensive to produce as all of the metal parts may be formed from stock material or as stampings.

Having now described my invention, what I claim as new and desire to secure by Letters Patent is:

1. In an automatic stop device for a radio receiver of the type including tuning elements, a screw-threaded operating rod operable to set the tuning elements, a nut having screw-threaded cooperation with said rod, means for preventing turning of said nut so that it will move lengthwise along the rod when the latter is turned, an indicator pointer secured at one end to said nut, a stop device for resisting continued turning of said rod after the nut has reached its extreme positions along said rod, a manually operable knob for turning said rod, and connecting means between said knob and said rod and normally providing a driving connection therebetween but being operable, upon actuation of

said stop device, to slip so that continued turning of the knob will not be communicated to said rod, said connecting means including a first disc secured to said rod, a second disc freely surrounding said rod and disposed face to face with said 5 first disc, a collar freely surrounding said rod and prevented from movement off the adjacent end thereof, the turning knob being secured to said collar, said collar having a reduced portion providing a shoulder between the second disc 10 and said turning knob, and a spring extending between said shoulder and the face of the second disc remote from the first disc.

2. In an automatic stop device for a radio receiver of the type including tuning elements, a 15 rotary screw-threaded operating rod operable to reset the tuning elements, a nut having screw-threaded cooperation with said rod, means for preventing turning of said nut so that it will move lengthwise along the rod when the latter is turned, an indicator pointer secured at one end to said nut, a stop device for resisting continued turning of said rod after the nut has reached its extreme positions along said rod, a manually operable knob for turning said rod, and connecting means between said knob and said rod and normally providing a driving connection therebetween but being operable, upon actuation of said stop device, to slip so that continued turning of the knob will not be communicated to said 20 rod, said connecting means including a first disc

secured to said rod, a second disc freely surrounding said rod and disposed face to face with said first disc, the bore of the second disc being substantially larger than the diameter of that portion of the rod which it encircles, a collar freely surrounding said rod and prevented from end-wise movement off the adjacent end thereof, the turning knob being secured to said collar, said collar having a reduced neck projecting into the bore of said second disc in order to maintain the latter concentric about the rod, a shoulder being formed at the rear end of said reduced neck, and a spring of spider formation having a central part bearing against said shoulder and the outer ends of radiating tongues bearing against the adjacent face of said second disc.
